PLAYING BOARD FOR TABLE BALL GAME

Robert L. Rienecker, 1524 Cabrillo Ave.,
Burlingame, Calif. 94010

Filed Dec. 12, 1968, Ser. No. 14,937

Term of patent 14 years

Int. Cl. D21—01

U.S. Cl. D34—5

FIG. 1 is an isometric view of a playing board for table ball game showing my new design;

FIG. 2 is a top plan view thereof; and

FIG. 3 is a front elevational view.

I claim:

The ornamental design for a playing board for table ball game, substantially as shown.
